UNITED STATES PATENT OFFICE.

EUGENE JACQUEMIN, OF KENT, WASHINGTON, ASSIGNOR OF ONE-HALF TO HENRY L. CHARLES, OF KENT, WASHINGTON.

TOY WHISTLE.

Application filed December 13, 1926. Serial No. 154,546.

The objects of my invention are, to provide, in its preferred embodiment, a whistle of flexible construction adapted to be marketed in a tube-like form, having exteriorly 5 no rough surfaces or outstanding projections, thus making it cheap and convenient for packing in a compact way and reducing the hazard of breakage; and, to afford such a device which is exceedingly simple in form 10 and inexpensive to produce.

In the accompanying drawing:—

Figure 1 is a side elevation of the device complete;

Fig. 2 a longitudinal section of the same, 15 the mouthpiece being disposed in operative position; and,

Fig. 3 a perspective showing the manner in which the device is utilized as a whistle.

The device is designed to be made preferably of flexible tubular stock such as rubber, either plain or reenforced with canvas, 20 candy, or any other suitable material. It comprises simply a section of such material having a kerf 1 diagonally disposed and extending through the greater portion of its 25 diameter, as indicated in Fig. 1. This kerf serves to separate the device into a body member 2 and a mouthpiece 3, having a flexible connection with said member, as at 4, 30 and also produces a thin edge 5 in the upper opening of the member. As it may be noted, the other end of said member is also open.

In operating the device, the body member 35 is grasped between the first and second fingers and the lower open end of the body member is closed by the thumb; the mouthpiece is then drawn back from said member by the teeth, as indicated in Fig. 3, and when a blast of air is forced through the mouth-

piece and against the thin edge 5 formed by 40 said kerf, a sharp whistling sound is produced.

Obviously, a device constructed of thin, tubular and metallic stock, and in the form shown in Fig. 2 will also function as a 45 whistle.

I claim:

1. A toy whistle, comprising a tubular body member open at each end, its upper end having its forward edge reduced in 50 thickness, and a tubular mouthpiece, open at each end and having its lower end of a form complementary to said upper end, hingedly secured to the member.

2. A toy whistle, made of a single piece 55 of flexible tubular stock, comprising a body member open at both ends, a mouthpiece, and an integral hinged connection between one end of said member and the mouthpiece. 60

3. A toy whistle, comprising a flexible tube having a diagonally disposed kerf adjacent one end, said kerf providing a tubular portion having an integral flexible connection with the other portion of the tube 65 adapted to function as a mouthpiece for the whistle when bent, through said connection, rearwardly of the last-named portion.

4. A toy whistle, comprising a tubular body portion and a tubular mouthpiece 70 hingedly secured to said portion and communicating therewith.

5. A toy whistle, made of a single piece of tubing, comprising a body member open at both ends, and a mouthpiece disposed at 75 one end, in angular relation with the member.

EUGENE JACQUEMIN.
